UNITED STATES PATENT OFFICE

93,566

DESIGN FOR A GAME APPARATUS

George H. Miner, Los Angeles, Calif.

Application July 5, 1934, Serial No. 52,467

Term of patent 7 years

To all whom it may concern:

Be it known that I, GEORGE H. MINER, a citizen of the United States, residing at 449 South Cloverdale, in the city of Los Angeles, county of Los Angeles, and State of California, have invented a new, original, and ornamental Design for Game Apparatus, of which the following is a specification, reference being made to the accompanying drawing, forming part thereof

and

Figure 3 is an end view thereof.
I claim:
The ornamental design for a game apparatus
as shown.

GEORGE H. MINER.
